(57) **CLAIM**

The ornamental design for a charging tray, as shown and described.

DESCRIPTION

FIG. 1 is a top view of a charging tray according to our new design;

FIG. 2 is a bottom view thereof;

FIG. 3 is a front view thereof;

FIG. 4 is a rear view thereof;

FIG. 5 is a left side view thereof;

FIG. 6 is a right side view thereof;

FIG. 7 is a front, right perspective view thereof;

FIG. 8 is a front, left perspective view thereof;

FIG. 9 is a rear, right perspective view thereof;

FIG. 10 is a rear, left perspective view thereof;

FIG. 11 is a cross-sectional view along lines 11-11 identified in FIG. 1;

FIG. 12 is a cross-sectional view along lines 12-12 identified in FIG. 1;

FIG. 13 is a cross-sectional view along lines 13-13 identified in FIG. 1;

FIG. 14 is a cross-sectional view along lines 14-14 identified in FIG. 1;

FIG. 15 is a cross-sectional view along lines 15-15 identified in FIG. 1; and,

FIG. 16 is a cross-sectional view along lines 16-16 identified in FIG. 1.

The broken lines depict environmental subject matter only and form no part of the claimed design.

1 Claim, 16 Drawing Sheets
